UNITED STATES PATENT OFFICE.

WALTER McLAREN, OF DAYTON, OHIO, ASSIGNOR TO THE McLAREN PRODUCTS CO., OF DAYTON, OHIO, A CORPORATION OF OHIO.

METHOD OF OPERATING MALE AND FEMALE MOLDS HAVING STRIPPER PLATES.

Application filed June 23, 1924. Serial No. 721,857.

To all whom it may concern:

Be it known that I, WALTER McLAREN, a citizen of the United States, residing at Dayton, in the county of Montgomery and State of Ohio, have invented a new and Improved Method of Operating Male and Female Molds Having Stripper Plates, of which the following is a specification.

My invention has for its particular object to provide an improved method of extracting ice cream cones and other forms of cup pastry from their baking molds. Cup pastry is usually made by a combined molding and baking process employing male and female molds. These molds are either of the solid female type or the split or divided type, the latter being used principally in the making of cake or sugar sweetened cones, and the former in the making of paste cones, that is, cones having but little, if any, sugar.

Heretofore numerous methods of extracting the cones from their molds have been used, among which is the use of a stripper plate for effecting the detachment of the cones from the male or female parts of the molds or both.

My present invention particularly has for its object to provide an extraction method for use in connection with such molds as employ stripper plates.

In order to obtain a clear understanding of my method of operation reference is made to the accompanying drawing, in which:

Figure 1 is a vertical longitudinal section of a male and female four unit mold of a type that may be employed in carrying out my invention.

Figure 2 is a cross section on the line 2—2 of Figure 1 with the core, mold and stripper plate in the position they assume when assembled, and the molds are free from a charge of batter.

Figure 3 is a section similar to Figure 2 indicating the position of the parts during the baking stage after the mold has been charged with batter and the core pressed down to its final position.

Figure 4 indicates the first step in carrying out my present extraction method.

Figure 5 indicates the second step in carrying out my method where split molds are employed.

Figure 6 indicates the final step of the method where the stripper has functioned to release the cone from the male element.

In the drawing, which is simply diagrammatic in its nature, 1 indicates the female mold which may be of sections or may be a mold of one piece, a sectional mold being illustrated in the drawing. 2 represents the core bar which carries the cores or male elements 3, and 4 indicates the stripper plate which fits snugly, but with a sliding fit, the necks 5 of the cores 3 and has up and down movement on such necks. The stripper plate 6 is supported from the core bar by pins or bolts 6 and springs 7 are interposed between the stripper plate 4 and the core bar, continuously tending to lower the stripper plate from the core bar, adjustable nuts 8 being provided to determine the maximum movement of the stripper plate under the tension of the springs 7. The stripper plate 4 may be caused to go through its cycle of movement in any desired way. Where the invention is employed in automatic machinery, however, the movements of the stripper plate 4 will be governed by cam track action but since that forms no part of my present invention (the method being independent of any particular apparatus employed) I have not illustrated any mechanism for operating the stripper 4 in the manner stated.

In carrying out my method of extracting the cones from the baking molds where the invention is used in connection with molds of the split type, the molds are charged with batter in any of the ways now known and the core is pressed to its finally seated position 90 to cause the batter to fill the mold cavity and the excess to be pressed out through the top of the mold cavity. The excess batter encountering the stripper plate 4 will force it up against the tension of the spring 7 and 95 flow out to form a head sheet 9 on the cone 10.

It is well known to those skilled in this art that the presence of sugar in ice cream cones causes an increased adherence of the material to the mold surfaces with which it is in contact. This is commonly known as "sticking". In order to free the cones properly from the molds of the type with which my invention is employed, I first effect a raising of the stripper plate 4 from the position indicated in Figures 1 and 3 sufficiently to break the adherence between the stripper plate and the head sheet 9 of the cone (see Figure 4). I next open the fe- 110

male molds, as shown in Figure 5, thereby freeing the outer surface of the cone 10 from the surfaces of the female molds leaving the cone adhering to the core 3. I next lower 5 the stripper plate into contact with the head sheet and further to cause it to force the cone longitudinally off the core and permit it to drop, as shown in Figure 6.

Where the invention is carried out with 10 a non-separable or solid female mold the surface configurations of the female mold cavity are so designed that the draft will be longitudinal or along the axial line of the cavity so that the cone can be pulled up out of 15 the female cavity without mechanical interlocking. When the invention is employed in connection with molds of the solid type I lift the core and stripper plate from the position shown in Figure 3 up out of the female 20 mold entirely while maintaining the position of the stripper plate with respect to the core bar. I next lift the stripper plate up out of contact with the head sheet 9 to release it from the head sheet 25 and then force it downwardly again into contact with the head sheet, and further, to cause it to strip the cone from the core; or the stripper plate may be raised to break the contact with the head sheet before the 30 core and cone are withdrawn from the female cavity. I prefer the former operation, however, because it increases the tendency of the cone to stick to the core rather than to the female mold and ensures the lifting out 35 of the cone from the female mold cavity.

The essential feature of my invention lies in first detaching the stripper plate from sticking engagement with the baked product before using the stripper plate to strip the 40 baked product from the core.

While my invention has particularly for its object the extraction of the cone from the mold, it also comprehends the operation of the stripper plate on the excess batter or 45 overflow by which the excess batter or over-

flow is evenly spread and its overflow resists sufficiently to form properly the mouth or edge of the cone.

From the foregoing description, taken in connection with the accompanying drawing, 50 it is thought the complete construction, operation and advantages of my invention will be clear to those skilled in the art.

What I claim is:

1. The method of extracting pastry products from male and female molds having stripper plates on the male element, said method including the steps of detaching the stripper plate from the baked product before using the stripper plate to detach the 60 baked product from the male element. 65

2. The method of extracting pastry products from male and female baking molds using stripper plates on the cores, said method comprising the detachment of the 65 stripper plate from the adhering surface of the baked product, detaching the baked product from the female mold and thereafter moving the stripper plate into pressure engagement with the baked article to 70 force it off the core. 75

3. The method of operating male and female baking molds having stripper plates on the male element adapted to rest on the female element when the male element is in 75 position on the same, said method comprising the raising of the stripper plate to permit excess batter to flow out of the molding cavity over the top surface of the mold between it and the stripper plate, maintaining the stripper plate in pressure contact with the overflow, effecting a separation of the baked product from the female mold while it remains on the male element, and breaking the adherence between the stripper plate and the baked product and subsequently using the stripper plate to force the baked product off the male element. 80 85

WALTER McLAREN.
